fifty per cent to J. H. Nicolini, Alameda, Calif.

Substitute for abandoned application Serial No.
49,543, November 13, 1935. This application
May 3, 1940, Serial No. 333,139

2 Claims. (Cl. 8—159)

My invention relates to improvements in washing machines and it consists in the combinations, constructions and arrangements hereinafter described and claimed.

In the standard washing machine the actual washing is accomplished by pushing the clothes back and forth through the water by different mechanical means. The action is so violent that it is the chief cause of abrading, tearing, and tangling the clothes. It is also necessary to pass the clothes at least three times through the wringer or spinner, once for each of two rinsings and again for wringing the water out of the clothes after the second rinsing.

The present washer is designed to wash, rinse the clothes as often as desired, blue, and then extract the water preparatory to hanging them on the line. All of this can be accomplished with only the initial handling of putting the clothes into the machine and the final handling of removing them from the machine.

The principal object of the invention is to provide a machine in which the clothes are agitated by the water instead of by a mechanical means. The movement of the water is such as to alternately squeeze and expand the clothes to simulate the actual hand washing. At the same time the water is forced through the clothes with the result that the clothes are efficiently cleaned without subjecting them to any abrading, tangling, or tearing action.

The device is extremely simple in construction and is durable and efficient for the purpose intended. The clothes basket is continuously rotated in one direction during the operation of the machine instead of being periodically reversed as is now the case in many washing machines. This will increase the life of the device.

Other objects and advantages will appear in the following specification and the novel features of the invention will be set forth in the appended claims.

My invention is illustrated in the accompanying drawings, forming a part of this application, in which—

Figure 1 is a vertical section taken substantially along the line 1—1 of Figure 2,

Figure 2 is a section along the line 2—2 of Figure 1,

Figure 3 is a section along the line 3—3 of Figure 1,

Figure 4 is a bottom plan view showing the legs in section,

Figure 5 is a section along the line 5—5 of Figure 1 on a reduced scale, and,

Figure 6 is a section along the line 6—6 of Figure 1.

In carrying out my invention, I provide a washing machine having an outer casing 1 with a closed bottom 2 and a hinged top cover 3. A vertical shaft 4 extends through a stuffing box 5 carried by the bottom 2 and supports an impeller 6 and a clothes basket 7. A bushing 8 is keyed to the shaft and is connected to the impeller and basket. The bushing spaces the basket 7 from the impeller 6 and provides a water passageway 9 between the two.

Figure 2 shows the impeller 6 as carrying arculate impeller blades 10 and the impeller is rotated in a clockwise direction when looking at the Figure and will not only throw the water outwardly due to centrifugal force, but will also cause the water to rotate in the same direction as the impeller. Figure 1 shows the bottom of the impeller closed by a disc 11 while the top is partly closed by a ring 12. The ring leaves a central opening 13 for the passage of water from the passageway 9 into the central portion of the impeller. Between the bottom disc 11 and the casing bottom 2 I dispose radially extending vanes 14, these vanes being secured to the disc and being used to throw any water flowing beneath the impeller, outwardly, whereby the portion of the casing bottom 2, disposed beneath the impeller 6, is kept free of water.

The clothes basket 7 is provided with a closed bottom 15 and a screen or perforated cylindrical side wall 16. The top of the basket is open and an inner cover 17 is spaced a slight distance 35 above the basket top and is secured to the outer cover 3 by supports 18. The diameter of the basket 7 is less than the diameter of the casing for providing an annular space around the basket for the circulation of water in a predetermined manner.

The casing 1 has an inwardly extending flange or ring 19 that is positioned substantially on the same level as the basket top. The inner edge of the flange provides an opening 20 just large enough to rotatably receive the basket. The casing has a second flange or ring 21 extending inwardly and lying in the same plane as the plane of the impeller ring 12. The inner edge 22 of the flange 21 is just large enough to provide a running fit for the rim of the impeller 6.

Figures 1, 2 and 5 show the flange 21 broken away as at 23 for providing an opening between the basket wall 16 and the casing wall. Two vertically disposed and radially extending partitions 24 and 25 lie between the flanges 19 and

21 carried by the casing 1, and between the basket and casing walls. These partitions are integral with the casing wall and are diametrically opposed to one another. The partition 25 extends upwardly from one edge of the opening 23 provided in the flange 21.

A third partition 26 parallels the partition 25 and extends upwardly from the other edge defining the opening 23 in the flange 21. This partition 26 is also integral with the casing wall and its inner edge terminates adjacent to the basket or clothes container wall. The partition 26 extends upwardly to the flange 19 and is integral therewith. The partitions 25 and 26 together with that portion of the casing wall disposed therebetween constitute a vertical fluid passageway A that leads upwardly from the casing bottom 2 to the flange 19. The impeller rotates the fluid in the casing bottom and beneath the flange 21. This fluid is then directed upwardly into the vertical passageway A by the curved deflector 27 that extends from the casing bottom and merges into the partition 26. The water or fluid in moving upwardly in the passageway A is forced into the basket 7 as shown by the arrows 28 in Figure 1.

One wall of a second vertical fluid conveying passageway B is formed by a partition 29 tangent to the basket 7 and extending from the inner edge of the partition 25 to the casing wall. The partition 29 is bounded at its top and bottom by the flanges 19 and 21. The other two walls of the vertical passageway B are the partition 24 and the portion of the casing wall 1 disposed between the two partitions 24 and 29. Figure 1 shows the downward flow of fluid in the passageway B and this is indicated by the arrows 30. The fluid upon reaching the flange 21 is deflected inwardly toward the center of the space 9. The rotating impeller creates a suction at the opening 13 and sucks the water into the center of the impeller.

A baffle 31 extends radially from the casing wall to the bushing 8 and this baffle prevents the rotation of fluid in the passage 9. The baffle is rigidly connected to a rod 32 and this rod is journaled in bearings 33. The rod extends above the flange 19 and is provided with an arm 34, see Figure 3, that carries a bolt 35 designed to enter one of two notches 36 and 37 in a quadrant 38 carried by the flange 19. When the arm 34 is swung from the full line position into the dotted line position shown in Figure 3, the baffle 31 is swung from the full line to the dotted line position shown in Figure 2. This permits the basket 7 and impeller to be lifted out as a unit through the opening provided when the cover 3 is swung into open position. When the baffle 31 is in operative position, it performs the additional function of locking the basket in place. The baffle 31 is curved slightly laterally for directing the fluid downwardly into the impeller.

The inner vertical edges of the partitions 24 and 26 are connected with an inner arcuate wall 39 that is disposed adjacent to the basket periphery. The top and bottom edges of the wall 39 terminate at the flanges 19 and 21. The fluid is prevented from passing through the space bounded by the flanges 19 and 21, the partitions 24 and 26, the casing wall 1 and the inner wall 39. A strip of metal 40, see Figures 1 and 2, extends between the partitions 25 and 26 and the top and bottom edges 41 and 42 of the strip lie in the same planes as the basket bottom 15 and ring 12. The strip 40 prevents the fluid flowing down-

wardly in the passageway B from passing directly across to the passageway A by means of the passageway 9 without first passing through the impeller 6.

Figure 3 shows the inner cover 17 provided with an eccentric opening 43 therein. A projection 44 carries a screen disc 45 that is disposed below the opening 43. The diameter of the disc is slightly larger than the opening. The purpose of this construction will be hereinafter described.

The mechanism for rotating the basket and impeller is shown in Figures 1, 4, and 6. A motor 46 has a shaft 47 provided with two ratchet pulleys 48 and 49. When the motor shaft is rotated in one direction, one pulley will be rotated while the other will idle, and when the shaft is rotated in the opposite direction the idling pulley will be rotated and the formerly rotated pulley will idle. Both ratchet pulleys are identical except as to size and the pulley 48 is diagrammatically shown in Figure 6. The pulley 48 has a central section 50 keyed to the shaft 47 and this central section has a ball ratchet indicated generally at 51 for positively connecting the pulley with the shaft when the shaft is rotated in a counter-clockwise direction as shown by the arrow. When the shaft is rotated in a clockwise direction, the pulley will idle. The pulley 49 operates in the same manner but in the opposite direction. The ball ratchet is not shown in the pulley 49 in Figure 1 because of the smallness of the showing.

The pulley 49 is connected to a pulley 52 by a belt 53. The pulley 52 in turn is connected to a pulley 54 by a stub shaft 55. A pulley 56 is connected to the shaft 4 and is actuated by a belt 57 passed around the pulley 54. The mechanism is such as to rotate the basket and impeller at a speed rapid enough for a thorough washing of the clothes.

The pulley 48 is connected to a small pulley 58 by a belt 59 and when the shaft 47 is rotated in a direction to rotate the pulley 48, the shaft 4 and basket will be rotated at a much higher speed for the drying operation. A reversing switch 60 is diagrammatically shown in Figure 1 and is used to rotate the motor first in one direction for the washing and rinsing operations, and then in the opposite direction for the drying operation.

Figure 4 shows the belt 53 passed around a pulley 61 that actuates a water pump 62. The bottom 2 of the casing has a depressed portion 63 in which the fluid can drain. An outlet pipe 64 leads from the depressed portion to the pump and is provided with a valve 65. A second pipe 66 leads from the pump 62 and a flexible pipe 67 is connected to the pipe 66 and can lead to a water drain, not shown, or the pipe can return the water back into the casing 1.

From the foregoing description of the various parts of the device, the operation thereof may be readily understood. The cover 3 is swung into open position and the casing is filled with soapy water to a predetermined height from the top of the basket. The clothes to be washed are then added and the motor started for rotating the basket and the impeller through the pulleys 49, 52, 54, and 56.

The rotating impeller will suck the water down through the passage B, across the passage 9 to its center, down into the impeller 6, and then out to the space in the casing bottom surrounding the impeller. The rotating water or fluid in the casing bottom is caught by the deflector 21 and is directed upwardly in the passage A. From the pas-

sage A the water enters the basket in the direction of the arrow C shown in Figure 5. The rotating basket will cause the water to leave the basket in the direction of the arrow D. A part of this water will pass downwardly in the passage B and the remainder will strike the partition 29 and will be deflected back into the basket in the direction of the arrow E. This will create a void or vortex eccentrically in the basket whose axis will substantially coincide with the center of the opening 43. During the continued rotation of the basket, some of the water will be forced out of the basket in the direction of the arrow D and into the passage B. Due to the whirling of the fluid in the passage B a part will strike the tangent partition 29 and will be deflected back into the basket or container in the direction of the arrow E, while the remainder will pass down the passage B and return to the impeller.

The result of these three currents of fluid indicated by the arrows C, D, and E in Figure 5, will cause the clothes to follow a particular path. It will be seen that the clothes as they are rotated will have a tendency to move outwardly due to centrifugal force. The basket wall will limit this outward movement. At the same time the projecting of water into the basket in the direction of the arrow C will cause the clothes to move inwardly away from the container wall at this point. The water entering the basket will not only move these clothes inwardly, but will force them against the rotating body of clothes, compressing the body of clothes to form them into an oval shape as shown at F in Figure 5. The continual rotation of the basket will cause the bundle of clothes to also rotate. It will therefore be seen that as the body of clothes is rotated, the clothes will have a tendency to expand during a part of the rotation, as shown at the points X—X, and will fill with water, and will be compressed during another part of the rotation, as shown at the points Y—Y, and will have the water squeezed therefrom. This action of alternately expanding and squeezing the body of clothes, simulates hand washing. The result is a perfect washing of the clothes in a short time and without any abrading or tearing effect.

In order to prevent the void or vortex in the water contained in the basket from extending from the top to the bottom of the basket, I provide the opening 43 in the inner cover 17. The basket in whirling, causes a portion of the water to flow over the basket top and to flow between the inner cover and flange 19 as shown by the arrows 68 in Figure 1. The water then will flow toward the opening 43 and will drop down into the basket as shown by the vertical arrows 69 in the basket. This water will agitate the water at the basket bottom and will tend to break the void or vortex formed by the rotating water. The result will be a more thorough agitation of the clothes with a more effective washing. The screen disc 45 prevents the clothes from passing up through the opening 43.

After the washing operation, the water may be drained by opening the valve 65 and allowing the pump 62 to pump the water. A rinse water may now be poured in through the open casing and the valve 65 closed and the motor again operated. After the rinsing operation, the water is again drained and a bluing or a second rinse water added. The machine is again operated and then the water is drained prior to the drying operation.

10 The clothes have not been removed from the basket between the washing and rinsing operations, and they are not removed prior to the water extracting operation. For this latter operation, the motor is reversed in its movement by the switch 60, and this through the large pulley 48 and its direct connection with the shaft 4 will rotate the basket at a high enough speed to extract the water.

15 After the water has been extracted, the clothes are removed for the first time and may be hung on the line to dry. It is obvious that in larger machines, more than one vertical "up" passageway A and "down" passageway B may be provided without departing from the spirit and scope of the invention.

20 While I have shown only one embodiment of my invention, it should be understood that various changes or modifications may be made within the scope of the appended claims without departing from the spirit of the invention.

25 This application is a substitute for my application Serial No. 49,543, filed Nov. 13, 1935, and now abandoned.

30 I claim:

35 1. The herein described method of washing clothes which consists in rotating the clothes about a vertical axis for causing them to move outwardly due to centrifugal force, confining the clothes in a circular area, directing water into a portion of this area and against the clothes for moving the clothes in this portion against the body of clothes for creating a squeezing effect upon this portion of the body of clothes, whereby the clothes will have a tendency to move outwardly during a part of their rotation and fill with water, and will be moved inwardly during another part of their rotation and will have water squeezed therefrom, thus simulating hand washing of alternately squeezing water from the clothes and then allowing them to again fill up with water.

40 2. The herein described method of washing a body of clothes in a cleaning fluid which consists in rotating the clothes about a vertical axis for causing them to move outwardly due to centrifugal force, confining the clothes within a certain area, and directing a part of the fluid against a portion of the clothes for moving this portion toward the center of the rotating body for squeezing the clothes in this portion, the directed part of the fluid progressively moving all of the clothes toward the center as the body of clothes is rotated.

JOHN E. W. BIRR.
